CLAIM

The ornamental design for a fur piece, as shown and described.

DESCRIPTION

FIG. 1 is a front elevational view of a fur piece showing my new design;

FIG. 2 is a side elevational view thereof;

FIG. 3 is a rear elevational view thereof;

FIG. 4 is a front elevational view of a fur piece showing a modified form of my new design;

FIG. 5 is a side elevational view of a fur piece showing another modified form of my new design.
